(No. Model.)

C. P. CARR.
QUADRUPLEX TELEGRAPHY.

No. 414,492.

Patented Nov. 5, 1889.

UNITED STATES PATENT OFFICE.

COURTLAND P. CARR, OF CHICAGO, ASSIGNOR OF ONE-HALF TO FRED P. MARSHALL, OF SOUTH EVANSTON, ILLINOIS.

QUADRUPLE TELEGRAPHY.

SPECIFICATION forming part of Letters Patent No. 414,492, dated November 5, 1889.

Application filed February 25, 1888. Serial No. 265,235. (No model.)

To all whom it may concern.

Be it known that I, COURTLAND P. CARR, of Chicago, in the county of Cook and State of Illinois, have invented certain new and useful Improvements in Quadruplex Telegraphy, of which the following is a specification, reference being had to the accompanying drawings, and to the letters of reference marked thereon.

10 My invention consists in certain improvements in the third coils of the neutral relay, and in the location of the condenser and adjustable resistance in the main and artificial lines in the arms of the Wheatstone bridge between the neutral and polar relays, whereby I am enabled to so regulate the time of the discharge of the condenser on a reversal at the distant station as to do away entirely with the false signal made by the armature of 15 the neutral relay, which enables me to operate the local circuit of the receiving-sounder directly by contacts on the front of the neutral relay-armature, as in the ordinary Morse sounder, and thus to dispense with the repeating-sounder and its circuit. I am also enabled to use but one condenser, which I find all-sufficient for the object in view, in place of two, as heretofore. These false signals are due to the change in polarity in the 20 coils of the neutral relay on the reversal at the distant station, which produces a momentary deadness in the cores while one charge goes out and the other comes in.

In the accompanying drawings, which illustrate my means for preventing a false signal in the neutral relay on a reversal at the distant station, Figure 1 is a plan view of the circuit-connections with the local circuits omitted, the artificial line being represented 25 in dotted lines; and Fig. 2, a view of my present arrangement of the line and third coils and armature of the neutral relay with the receiver-circuit operated thereby.

L, Fig. 1, is the main line, A L showing the 30 artificial line.

B is the main-line battery; A, the neutral and D the polar relay.

E E' F F' are the double coils of the neutral relay, differentially wound in the usual 35 way.

R is the adjustable resistance, consisting, as

shown, of two equal and independently-adjustable parts $r r'$ on the main line L and artificial line A L, between the neutral and polar relays A and D, as described. The part 55 r of the resistance R consists of a number of resistance-coils located in the main line L, between the polar and neutral relays, so as to regulate the time of the passage through the neutral relay of the current coming from the 60 distant station. r' consists of a similar resistance located in the artificial line A L, also between the neutral and polar relays, by which the time of discharge of the condenser through the third coils on a reversal at the 65 distant station can be regulated.

G G' are the third coils, connected by the line L' to the main line, between the resistance r and the polar relay, and to one plate 70 of the condenser C.

A' L' represent the wire connecting the other plate of the condenser to the artificial line between the part r' of the resistance and the polar relay. In this arrangement, in which the point of bridging is between the neutral 75 and polar relays, the effects of a reversal at the distant station reach the bridge and discharge the condenser at exactly the same time that the effect enters the line-coils of the neutral relay, and by introducing a little 80 resistance in the main line it allows the condenser to discharge an instant sooner than it affects the line-coils of the neutral relay, giving the time of discharge in the third coils a chance to be adjusted and preventing the 85 false signal. It is thus seen that by adjusting the resistances $r r'$ with respect to each other the times of the discharge through the condenser-circuit and of the passage of the current through the neutral relay may be regulated with respect to each other, so as to do 90 away with the false signal.

A, Fig. 2, is the neutral relay having the armature a, with cross-pieces a' a', and pivoted at b.

G G' are the third coils, and E E' F F' the differentially-wound main-line coils.

R S is the receiving-sounder; L C, the local circuit; L B, the local battery, and x y the contact-points for operating the local circuit. 100 It is thus seen that I place an equal adjustable resistance in the main and artificial

lines in the arms of a Wheatstone bridge made between the neutral and polar relays, and connect up the third coils of the neutral relay through a single condenser therewith. 5 This arrangement of the third coils and condenser enables me to regulate the time of the discharge of the latter through the third coils, so as to be simultaneous with the passage of the current on the main line, and by employing 10 an adjustable condenser to regulate the strength of the discharge and produce a synchronous effect on the relay-armature I thus do away with the false signal and can operate the circuit of the receiving-sounder 15 directly by contacts on the front of the relay-armature, in place of mediating through back contacts and a repeating-sounder, as heretofore. When the third coils are made adjustable to the armature of the neutral relay, the 20 condenser may be non-adjustable, as the approach or withdrawal of the third coils answers the same purpose. I also wind the coils of the condenser-circuit on separate cores, and preferably place them above the main-line coils to act on the armature in the same 25 direction. They, as well as the main-line coils, are made adjustable by any well-known means; and I am thus enabled, further, to regulate the effect of the condenser- 30 discharge on the armature by approaching or withdrawing the electro-magnets to or from the armature. The position of the third coils above the line-coils, and nearer the extremity of the armature, has the further advantage of affording an increased leverage on 35 the latter.

All of the coils may be of the same size and should be very short, in order not to hold the discharge and cause the armature to work 40 thick, the resistance of the third coils being from two hundred to three hundred ohms; and the armature is provided with two cross-pieces, one for each set of coils, and has a retracting-spring, similar to that of a Morse relay, to pull it open when no current is passing in the coils. 45

In addition to the increased facility in the transmission and reception of messages derived from the foregoing novel organization 50 of the different elements of the quadruple, I am enabled to effect a considerable saving in

expense arising out of the simplicity of the arrangement, whereby I dispense with the repeater, its local circuit, and one condenser.

I do not limit myself to the use of a resistance located in the arms of a Wheatstone battery between the neutral and polar relays when used with independent third coils in the condenser-circuit alone; neither do I limit myself to the use of my invention in quadruplex telegraphy, as it is equally capable of application to multiplex telegraphy by making the proper adaptation. 55 60

Having thus described my invention, what I claim as new, and desire to secure by Letters Patent, is—

1. In a quadruplex telegraph, the combination, with a main line, a neutral relay located therein, and its armature, of an electro-magnet adjustable to and from the armature of the neutral relay, a condenser, and condenser-circuit in which the adjustable electro-magnet is included, substantially as described. 70

2. In a quadruplex telegraph, the combination, with the main line, the artificial line, and the battery, of the neutral and polar relays, connected as described, adjustable resistances r r' , interposed between the neutral and polar relays on the main and artificial lines, respectively, between the point of bridging and the neutral relay, an electro-magnet, a condenser and condenser-circuit between the main and artificial lines, in which the electro-magnet is included, and a neutral relay-armature common to both the relay and the electro-magnet, substantially as and for the purpose described. 75 80 85

3. In a neutral relay for quadruplex telegraphy, the combination, with the relay electro-magnet, of the adjustable and independent electro-magnet located above and acting in the same direction as the relay-magnets, the armature having two cross-pieces, one for each set of coils, and means for retracting the armatures, substantially as hereinbefore set forth. 90 95

In testimony whereof I have hereunto set my hand and seal.
